PLATE FINISHING MACHINE

John A. Isbell, Plainfield, N. J., assignor to Wood
Newspaper Machinery Corporation, Plainfield,
N. J., a corporation of Virginia

Application February 28, 1939, Serial No. 258,971

6 Claims. (Cl. 29—21)

This invention deals with the type of machine where printing plates, particularly stereotype plates, are shaved to the proper thickness and delivered, ready for placing on the printing press.

- 5 The machine is provided with an inspection platform on which the plate is placed. After inspection the plate is allowed to pass into the machine where the concave surface of the semi-cylindrical plate is shaved and the beveled edges 10 are trimmed. After shaving and trimming, during which process the plate is clamped into and unclamped from the shaving arch, it passes on the delivery end of the machine, ready to be placed on the printing press.
- 15 In a machine of this character now in use considerable difficulty is encountered with weakness in the frame structure and in keeping the arch set concentric with the knife bar. It is therefore the purpose of this invention to provide a 20 device which will insure strength and accuracy with provisions for adjustments to obtain the original accurate setting.

The shaving arch cast as an integral part of the base is the main feature of the machine. 25 This one-piece construction insures that, when a successive number of plates is machined, each will be held in exactly the same position in regard to the knife bar, and thereby produce a series of plates which are machined exactly alike.

30 The knife bar is mounted in heavy duty bearings and firmly secured to the same base that contains the shaving arch. Adjustable gibs are provided to set bearing housings accurately.

Other objects and advantages of the invention 35 will appear hereinafter.

Reference is to be had to the accompanying drawings, in which:

Fig. 1 is an elevation of a machine embodying this invention, showing particularly the main frame and knife bar;

40 Fig. 2 is a cross-section on the line 2—2 of Fig. 1 and shows the plate in its lowered position on the left hand side of the figure and in the raised position on the right hand side of the figure, illustrating how the plate is clamped in the arch;

45 Fig. 3 is an elevation of the adjusting bearings, and

Fig. 4 is a plan view of the bearing.

Fig. 1 shows the main frame 1 whose ends are 50 suitably machined to accommodate an inspection bracket 2 and a delivery bracket 3. In the main frame 1, pads 4 and 5 are machined with suitable grooves to engage tongues 6^a and 7^a on bearing housings 6 and 7 respectively. Said 55 housings carry heavy duty clearance-free bear-

ings that rotatably mount a knife bar 8 in such position that its axis coincides with the center of the arch. The above grooves are machined at right angles to the axis, thereby allowing transverse adjustment but definitely locating the knife bar 8 longitudinally.

5 The knife bar 8 derives its motion from a motor 9 which is fastened to the underside of the bracket 2. A motor pinion 10 drives a gear 11 attached to a worm shaft 12. A worm 13 10 mounted to the shaft 12 operates a worm wheel 14, which in turn drives a worm 15 which is secured to a shaft 16. The worm 15 operates a worm gear 17 keyed to the knife bar 8. In this manner the motor 9 rotates the knife bar 8. 15

Bolted to the inside of the shaving arch 16 of the main frame 1, as shown in Fig. 2, is a water cooled liner 16^a which engages the printing surface of a plate P2, as shown on the right hand side of Fig. 2. Plate lifters 18 and 19 are provided to raise the plate, by mechanism not shown, from the position P1 to the position P2 against the liner 16^a and hold the plate securely while the knife bar 8, carrying knife blades 20 and 21, shaves the inner surface of the plate to 25 finish said plate to the proper thickness. A trimming tool 22 also attached to the knife bar trims the curved edge of the plate.

The bearing housing 6 shown in Fig. 3 and in Fig. 4 is securely bolted to the main frame 1 by 30 bolts 23. Slotted holes in the base of said housing allow adjustment by means of a gib 24. It should be understood that gibs are provided at each end of the bearing housings. Adjusting screws 25 and 26 threaded in to the gib 24 permit said gib to be set before being fastened by a screw 27 to the main frame 1. 35

Laminated shims 28 are provided between the bearing housing 6 and the main frame 1 to adjust the vertical position of the knife bar 8. 40

The bearing housing 7 is mounted to the frame 1 in the same manner as the housing 6.

It is therefore evident that when the knife bar is properly set in the main frame, all plates 45 finished in the shaving arch will be machined exactly alike.

Having thus described my invention and the advantages thereof, I do not wish to be limited to the details herein disclosed, otherwise than as 50 set forth in the claims, but what I claim is:

1. A plate finishing machine, including a main frame, a shaving arch, and a shaving knife, adjustable bearings in which said shaving knife is mounted, said main frame and shaving arch be- 55

ing made in one piece, and a water cooled liner carried in the shaving arch.

2. A plate finishing machine, including a main frame, a shaving arch, a shaving knife, and a knife bar, said main frame and shaving arch being made in one piece and said shaving knife being mounted by the knife bar in adjustable bearings.

3. A plate finishing machine, including a main frame and a shaving arch integral with each other, a knife bar mounted in adjustable bearings, said knife bar carrying a plurality of knives for finishing the concave surface of a printing plate.

4. A plate finishing machine, including a main frame integral with a shaving arch, a liner concentric with the inner surface of the shaving arch, means for lifting a printing plate and clamping it in the arch against said liner, a knife

bar mounted in adjustable bearings and a plurality of knives carried thereon for finishing the concave surface of the printing plate.

5. A plate finishing machine, including a main frame and a shaving arch integrally connected, a liner concentric with the inner surface of the shaving arch, means for lifting a printing plate and clamping it in the arch against said liner, a knife bar concentric with the arch, adjustable bearings in which said knife bar is mounted and a plurality of knives carried on the bar for finishing the concave surface of the printing plate.

6. A plate finishing machine, including a main frame and a shaving arch integral with each other, a knife bar mounted in adjustable bearings, a knife secured to said knife bar for finishing the concave surface of a printing plate.

JOHN A. ISBELL.
